(57) **CLAIM**

The ornamental design for medical equipment as shown and described.

DESCRIPTION

The application contains at least one drawing executed in color. Copies of this patent with color drawings will be provided by the Office upon request and payment of the necessary fee.

FIG. 1 is a front view of a medical equipment showing our new design; and,

FIG. 2 is a rear view thereof.

The broken lines and surfaces they enclose show portions of the medical equipment that form no part of the claimed design.
